UNITED STATES PATENT OFFICE.

HENRY CLAY BASCOM, OF LANSINGBURG, AND EDWARD AMBROSE, OF TROY, ASSIGNORS TO THE SYRACUSE STOVE WORKS, OF SYRACUSE, NEW YORK.

DESIGN FOR A STOVE OR RANGE.

SPECIFICATION forming part of Design No. 24,408, dated June 18, 1895.

Application filed May 9, 1895. Serial No. 548,769. Term of patent 7 years.

To all whom it may concern:

Be it known that we, HENRY CLAY BASCOM, residing at Lansingburg, and EDWARD AMBROSE, residing at Troy, in the county of Rensselaer, State of New York, citizens of the United States, have invented and produced a new and original Design for Stoves or Ranges, of which the following is a specification, reference being had to the accompanying drawing, showing a part thereof.

The single figure of the drawing shows in perspective the design, which lies in the peculiar decoration and appearance of the front and ends of the stove or range. The figure being in perspective, shows only one end thereof, exactly as is seen by the observer, but the other end corresponds exactly in design to the one here shown.

The range here illustrated is what is commonly known as a single oven range with low closet and high shelf, and its construction to some extent limits the character of the design.

The leading features of my design are the four front doors, differing in size, and variously but harmoniously decorated, so that the front of the range presents the appearance of four decorated panels of unequal size. These panels or doors are indicated by the letters A, B, C, D.

The two panels on the left are of the same width, and are decorated in relief with two rather large figures composed of scroll work and volutes arranged near their side edges, substantially filling those side edges from top to bottom, and having curved extensions along the upper edge, extending nearly to the middle of that edge. In panel A these two figures E E consist of rather large volutes 1—1 in the upper corners connected to volutes 2—2 in the lower corners by sections of scroll work 3—3. They also have the extensions 4—4 of scroll work, extending inward along the upper edge of the door. The form of these figures E E leaves a plain center on the panel between them, which is substantially filled with an elevated shield F, having its upper and side margins 5—5—5 decorated with scroll work in bas-relief, as here shown, the center 6 being left plain to be inscribed with

any desired name. Between the figures E E and the shield F is left a plain band 7—7 undecorated.

Panel B has two marginal figures G G composed of volutes and scroll work, similar to figures E E on panel A, having volutes 8—8 and 9—9, which are arranged nearer together than the corresponding volutes 1—1 and 2—2 on panel A, on account of the lesser height of the panel or door B, and which have inward extensions 10—10 of scroll work along the upper edge. In the space between these figures G G is arranged a figure H, substantially triangular in its outline, having its base arranged near the bottom of the door and composed of two rather large scrolls 11—11 with the scroll 65 work 12 and the point 13 extending upwardly from them. Between the figures G G and the triangular figure H there is an undecorated portion or plain band 14—14.

The lower part of panel C is filled with the 70 damper holes 15, and its upper part substantially filled with a combination of scroll work and volutes arranged in two figures I I, one on each side of the door. These figures consist each of rather a large volute (16—16) arranged near the upper part of the door with downwardly extending scroll work (17—17).

Panel D is substantially filled with a single figure K composed of volutes and scroll work arranged in a sort of bouquet arrangement, rising up from near the bottom of the door and recurring toward the bottom. What may be called the stems 18 of these volutes and scrolls are inclosed within a band or ring 19, having its outward margin scalloped. 85

The main portion of each end of the range is divided into two sections, the upper M, and the lower N, which sections are both decorated with substantially the same decorations in bas-relief. Below the middle of M are arranged the damper holes 20 underneath which is a band decorated with rather a large double volute 21, the two volutes being arranged close together in the center, with scrolls extending outwardly and horizontally from each. Above the damper holes 20 is the larger portion of M, which is filled with a single figure O, consisting of scroll work rising in a

sort of double bouquet arrangement from a ring or band 22, having a scalloped outer margin. The upper portion 23 of figure O is the largest and is composed of scroll work curving outwardly and downwardly toward both sides from the center, and substantially filling the upper part of section M. Beneath this is a similar but smaller arrangement of scrolls 24 curved outwardly and downwardly in both directions. Figure P, which substantially fills section N, is almost exactly the same as figure O just described.

The four front doors or panels and the end section of the stove are arranged in combination with a bottom plate Q Q connected by uprights R R to the middle plate S S S, said plates Q Q, S S S, and uprights R R being similarly and suitably ornamented in a simple manner.

All the decorations on the range herein shown and described are in relief.

Having thus described our invention, what

we claim, and desire to secure by Letters Patent, is—

1. In a design for a range the panel A, substantially as shown.
2. In a design for a range the panel B, substantially as shown.
3. In a design for a range the panel C, substantially as shown.
4. In a design for a range the panel D, substantially as shown.
5. The design for a range, substantially as here shown and described.

In witness whereof we have hereunto set our hands, in the presence of two attesting witnesses, at Troy, in the county of Rensselaer, in the State of New York, this 29th day of April, 1895.

HENRY CLAY BASCOM.
EDWARD AMBROSE.
